(57) **CLAIM**

The ornamental design for a tray, as shown and described.

DESCRIPTION

FIG. 1 is a top perspective view of a first embodiment of a tray, showing our new design.

FIG. 2 is a bottom perspective view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof.

FIG. 8 is a bottom plan view thereof.

FIG. 9 is a top perspective view of another embodiment of a tray, showing our new design.

FIG. 10 is a bottom perspective view thereof.

FIG. 11 is a front elevational view thereof.

FIG. 12 is a rear elevational view thereof.

FIG. 13 is a left side elevational view thereof.

FIG. 14 is a right side elevational view thereof.

FIG. 15 is a top plan view thereof.

FIG. 16 is a bottom plan view thereof.

FIG. 17 is a top perspective view of another embodiment of a tray, showing our new design.

FIG. 18 is a bottom perspective view thereof.

FIG. 19 is a front elevational view thereof.

FIG. 20 is a rear elevational view thereof.

FIG. 21 is a left side elevational view thereof.

FIG. 22 is a right side elevational view thereof.

FIG. 23 is a top plan view thereof.

FIG. 24 is a bottom plan view thereof.

FIG. 25 is a top perspective view of another embodiment of a tray, showing our new design.

FIG. 26 is a bottom perspective view thereof.

FIG. 27 is a front elevational view thereof.

FIG. 28 is a rear elevational view thereof.

FIG. 29 is a left side elevational view thereof.

FIG. 30 is a right side elevational view thereof.

FIG. 31 is a top plan view thereof.

FIG. 32 is a bottom plan view thereof.

FIG. 33 is a top perspective view of another embodiment of a tray, showing our new design.

FIG. 34 is a bottom perspective view thereof.

(Continued)

FIG. 35 is a front elevational view thereof.
 FIG. 36 is a rear elevational view thereof.
 FIG. 37 is a left side elevational view thereof.
 FIG. 38 is a right side elevational view thereof.
 FIG. 39 is a top plan view thereof.
 FIG. 40 is a bottom plan view thereof.
 FIG. 41 is a top perspective view of another embodiment of a tray, showing our new design.
 FIG. 42 is a bottom perspective view thereof.
 FIG. 43 is a front elevational view thereof.
 FIG. 44 is a rear elevational view thereof.
 FIG. 45 is a left side elevational view thereof.
 FIG. 46 is a right side elevational view thereof.
 FIG. 47 is a top plan view thereof; and,
 FIG. 48 is a bottom plan view thereof.
 The broken lines showing text and measurement marks in the tray are for the purpose of illustrating unclaimed subject matter and form no part of the claimed design.
